APPARATUS FOR THE ELECTROLYTIC
MANUFACTURE OF METALS, AND CHIEFLY
OF MAGNESIUM

Alfred Claude Jessup, Clamart, France

Application May 25, 1931, Serial No. 539,946, and
in Germany May 31, 1930

14 Claims. (Cl. 204—19)

During the electrolysis of a molten metallic salt carried out in a tank fitted with an anode or anodes positioned near the center of a polygon formed by the cathodes, the inventor has observed 5 that a circular current or rotary movement is produced in the electrolyte around the anode, and that this current or rotary movement tends to drive the metal towards the periphery of the tank.

10 The present invention consists in utilizing this effect, when the density of the electrolyte is greater than or substantially equal to that of the metal obtained by the electrolysis, and in providing recesses or offsets or pockets on the periphery, 15 said pockets being protected against the said circular current, whereby the metal will more readily collect in the said pockets.

Furthermore, in order the more effectively to protect the metal in the said pockets from the 20 effects of the said circular current, the pockets are fitted with vertical partitions, preferably made of some refractory material, which extend from the top of the electrolytic vessel downwardly and dip into the electrolyte, which prevent the current from affecting the part in the 25 rear of the said partitions.

Hitherto it has been the general practice when 30 utilizing such pockets fitted with partitions dipping into the electrolyte, to place the cathodes within the said pockets. This was due to the erroneous belief that the metal would not accumulate and remain within the said pockets unless produced in situ, and to the fact that it had not so far occurred to the designers of electrolytic 35 tanks to make use of the said circular current or rotary movement observed by the inventor.

However the placing of the cathodes within the pockets gives rise to two grave obstacles in the carrying out of a satisfactory and economically cheap electrolysis of the metal salt in question. Firstly the cathodes are of necessity situated a long distance from the anode or anodes thus greatly increasing the resistance of the bath and the consumption of electric energy. 45 And secondly it has been found that if the current flowing between the anode and the cathode passes through the said partition of refractory material, the life of this partition is very greatly reduced, due to the deposition of conducting particles of metal within the interstices of the refractory material. In the process according to the present invention, these two difficulties are entirely obviated. The cathodes are situated in the central portion of the electrolytic vat and 50 outside of the pockets, so that no current passes

through the partitions, their life being correspondingly very greatly prolonged; and in order to reduce the resistance of the bath to the minimum compatible with a good current efficiency, the cathodes are placed as near to the anode or 60 anodes as the dispersion of the chlorine or other gas evolved at the anode will permit.

The accompanying drawing shows by way of example only, a constructional form of electrolytic tank in conformity to the invention. 65

Figure 1 is a plan view of the apparatus.

Figure 2 is a central vertical section of same.

In the example herein represented, the electrolytic tank 1 has the shape of a square, at whose angles are formed the pockets in the shape of 70 offsets 2. The anode 3 is substantially at the center of the tank, and the cathodes 4 are positioned outside of the pockets 2 and at the middle of the sides of the square formed by the tank. The metal is deposited on the cathodes 4 and is 75 drawn forward with the circular current or gyroscopic motion of the bath along the walls of the tank, and it collects in the said pockets 2, in which it is out of the path of the circulating current, and is protected from the action of the gas given 80 off at the anode, by suitable partitions 5, of which the lower end dips a short distance into the bath. It will be understood that if several anodes are used they will be grouped at near the center of 85 the cell.

It should be further remarked that it is possible to use in certain cases the effects of the differences of variation of density of the metal and the electrolyte. Thus if the tank is lined with a heat-protecting covering, with the exception 90 of pockets in the form of recesses 2 in the tank, heat radiation will take place, thus reducing the temperature of the material in the pockets 2 with reference to the central part of the tank. If the densities of the magnesium and the electrolyte are 95 substantially equal in the tank, and especially if the magnesium is somewhat lighter than the electrolyte, the magnesium will float on the surface in the said offsets, since the variation of the density of the magnesium is less than that of the electrolyte for the differences in temperature prevailing in the said tank and in the pockets 2. Obviously, this natural cooling may be increased (or replaced) by an artificial cooling of the said 105 pockets. In this manner, the metal can be readily removed from the said offsets.

It is however not necessary in order to put the invention here described into practice, to build out the pockets in the form of recesses, as illus- 110

trated and modifications within the scope of the claims are included herein.

Having now particularly described and ascertained the nature of my invention and in what manner the same is to be performed, I claim:

- 5 1. A cell for electrolysis of a fused metallic salt, comprising an anode located in the central part of the area of the cell, pockets in which the material is relatively quiet at the periphery of the 10 area of the cell, means for protecting the material in said pockets from the gyratory movement of the bath in the main part of the cell, and cathodes situated outside said pockets, but within the said cell.
- 15 2. A cell as set forth in claim 1, in which the cathodes are placed between the pockets, and nearer to said anode than are said pockets.
3. A cell as in claim 1, in which the pockets are at the exterior of said cell, extending outwardly from the periphery of the main portion 20 of the cell.
4. A cell as in claim 1, polygonal in cross section, with the pockets located at the angles of the polygon.
- 25 5. A cell as in claim 1, in which the means for protecting the material in the pockets from strong movement, is a wall dipping down into the electrolyte.
- 30 6. A cell as in claim 1, having partition walls extending downwardly into the electrolyte in the cell, the same depending from the cover of the cell, and capable of isolating the atmosphere over the portion of the electrolyte in the pocket from the atmosphere over the electrolyte in the 35 cell proper.

7. A cell as in claim 1, having provision for allowing cooling the material in the pockets.

8. A cell as in claim 1, having a lagging on the exterior of the main portion of the cell.

9. A cell for electrolysis of a fused metallic salt, and particularly suitable for the electrolysis of fused magnesium chloride, comprising an anode located in the central portion of the cell, restricted sections of relative tranquillity at the periphery of the cell constituting pockets where the metal can collect, means for protecting the material in the said pockets, from the gyratory movement of the bath in the main part of the cell, and cathodes situated outside said pockets, but within said cell.

80 10. A cell as set forth in claim 9, in which the means for protecting said pockets from the gyratory movement of the bath is the construction of said pockets as off-sets from the periphery of the cell.

85 11. A cell as set forth in claim 9, in which the pockets are situated at the angles of the polygon formed by the sides of the cell.

12. A cell as in claim 9, in which the means for protecting said pockets from the gyratory movement of the bath is a wall dipping down into the electrolyte.

100 13. A cell as in claim 9, having walls dipping into the electrolyte, forming pockets at the periphery of the cell, said walls being made of refractory material, whose lower end dips only a short distance into the bath.

105 14. A cell as in claim 9, having a plurality of anodes located in the central portion of the cell.
